UNITED STATES PATENT OFFICE.

ROBERT S. PRINGLE, OF BRADFORD, PENNSYLVANIA, ASSIGNOR TO THE E. I. DU PONT DE NEMOURS POWDER COMPANY, OF WILMINGTON, DELAWARE, A CORPORATION OF NEW JERSEY.

MECHANISM FOR DELIVERING A PLURALITY OF TORPEDOES SIMULTANEOUSLY IN A WELL.

949,778.

Specification of Letters Patent. Patented Feb. 22, 1910.

Application filed March 17, 1909. Serial No. 483,938.

To all whom it may concern:

Be it known that I, ROBERT S. PRINGLE, native citizen of the United States, residing at Bradford, county of McKean, and State 5 of Pennsylvania, have invented a new and useful Improvement in Mechanism for Delivering a Plurality of Torpedoes Simultaneously in a Well, of which the following is a full, clear, and exact description, reference being had to the accompanying drawings, which form a part of this specification.

In delivering a plurality of torpedoes in a well, the general method now in use is to lower each torpedo separately into the 15 well. The difficulties and dangers of this method are quite obvious.

The object of my invention is to provide a construction of coupling which will enable a plurality of these torpedoes to be coupled 20 together before being lowered into the well and to enable them when coupled to be readily lowered into the well.

Speaking generally, I provide the upper portion of each torpedo with a ring provided with a plurality of depending lugs spaced apart around the ring, and the upper portion with a series of projecting lugs spaced apart a like distance with that of the lugs on the upper portion of the torpedo. 25 By this means the bottom or lower portion of each torpedo may be connected with the upper portion of another torpedo. The top ring of the last torpedo is connected to an independent ring similar to the rings connected to the lower portion of the torpedoes, but to which is pivoted a bail to be connected with the lowering rope or cable. I also use a plate which encircles the upper portion of each torpedo, the face of which 30 is of such size as to be greater than that of the projecting pipe from the well so that each torpedo can be brought to the mouth of the pipe, lowered therein until held by the plate at the mouth of the pipe until the 35 next succeeding torpedo is elevated and coupled to the preceding torpedo, when the plate of the lower torpedo may be released and the two torpedoes lowered in the pipe until the plate of the second torpedo rests 40 on the top of the pipe when the operation of coupling another torpedo may be carried out. This continues until the desired 50 number of torpedoes have been coupled to-

gether, when the top of the last torpedo is coupled, to the ring carrying the bail, which 55 bail is attached to the lowering cable and the plurality of torpedoes simultaneously lowered into the well. By this arrangement, I am enabled to couple up at the mouth of the well, a plurality of torpedoes, 60 and simultaneously lower them into the well.

In the following description, the plate itself, its purpose for elevating a torpedo to the mouth of the well and holding a torpedo there until the lowering rope or cable is 65 attached to it, is only new with me as an element of my means for coupling a plurality of torpedoes together at the mouth of the well and attaching the ring with bail attached thereto, to the top of the final 70 torpedo. I will however in the embodiment of my invention disclosed in the drawings illustrate that form of plate.

In the drawings: Figure 1 is a sectional view showing a number of torpedoes suspended in the mouth of the well. Fig. 2 is an enlarged view of torpedo broken away to show couplings. Fig. 3 is a plan view of upper coupling. Fig. 4 is section on line 4—4, Fig. 2. Fig. 5 is a detail plan view 80 of supporting plate. Fig. 6 is a section on line 6—6, Fig. 5. Fig. 7 is a section on line 7—7, Fig. 5. Fig. 8 is a section on line 8—8, Fig. 9. Fig. 9 is a plan view of bail ring. 85

a is the well, *b* the pipe projecting therefrom. In practice this pipe projects about three feet above the mouth of the well.

c is the can containing nitro glycerin or other explosive and forming the torpedo. 90 Secured to the top of this can by rivets or bolts is the ring *d* which may be a casting and of cast iron. The upper portion of this ring *d* has the flange *e*, in the face of which is formed the groove *f*. Above this groove 95 are the projecting lugs *g* which are spaced apart around the ring *d*. Secured to the lower portion of each of the torpedoes, except the initial torpedo, is a ring *g* projecting below said torpedo and adapted to envelop the upper portion of ring *d*. This ring *g* has the inwardly projecting lugs *h* 100 spaced apart corresponding to the lugs *g*.

g, g are two jaws, each having the projecting portion *h* having an orifice *i* through 105 which orifices the bolt *j* secured on the un-

der surface by nut *k* passes, thus forming a hinge for the jaws. The central or main portion of each of these jaws has a vertical curved surface provided with an inwardly projecting flange *m*.
n, *n*, are brass plates or bushings having the groove *o* in which the flange *m* enters. Each of these plates *n* has the inwardly projecting flange *p* adapted to enter the groove *f* in the flange of ring *d*. These plates are secured to their respective jaw members by means of set screws *q*. The flat horizontal surface of the plates *n* of the jaws *g*, *g* are of such width as to rest securely in the top 15 of pipe *b*. Each of these jaws *g*, *g*, is also provided with a projecting arm *r*. To one of these arms is pivotally secured the strap *s* and in this strap is pivoted the cam *t* provided with the operating handle *u*. When 20 the jaws *g*, *g*, are pivotally connected together, as described, they are encircled around the ring *d* so that the flanges *p* enter the groove *f*. The arms *r*, *r* are then moved toward each other and the strap *s* 25 brought over the other jaw *g* and the arms *r*, *r* moved until the flanges *p* are securely fitted in the groove *f* when the cam is operated to lock the two jaws fixed in that position. To the main body of each of the jaws 30 is pivotally connected a bale *v* by which the jaws are connected to the elevator. The elevator then lifts the can. The can is swung over and lowered until it enters the pipe *b* and the flat surface of the jaws rest upon the top of said pipe securely holding the torpedo. When in this position another torpedo is lifted in the same manner and lowered until the ring *41* envelops the upper 35 end of ring *d*. The lugs *42* passing down between the lugs *40*, and the ring *41* turned so that lugs *42* and *40* interlock, when the jaws may be removed from the first torpedo, and by the jaws holding the second torpedo, both torpedoes may be lowered in the pipe 40 45 until the jaw plate of jaws holding the second torpedo rests upon the top of the pipe. This is continued until the desired number of torpedoes have been assembled together, when the ring *44* shown in Fig. 9 with its 50 bale *1* is attached to the upper ring of the last torpedo. This ring is similar to the rings *41*, having similar inwardly projecting spaced lugs *42* interlocking with the lugs *40*. It has also the pivoted bail *43* attached 55 thereto. This bail is connected to the lowering cable or rope and the plurality of cans or torpedoes lowered into the well. If desired the rings *d* and *40* and *d* and *44* may be further secured together by the pin *45* in 60 the orifice *46* in rings *d*, *40* and *44*.

Having now fully described my invention, what I claim and desire to protect by Letters Patent is:

1. A plurality of explosive cans, or torpedoes, one having a projecting ring se-

cured to its upper portion, the other a projecting ring secured to its lower portion, the first mentioned ring having interspaced lugs projecting from and around its outer surface, and the other ring having interspaced lugs projecting from and around its inner surface. 70

2. An explosive can, or torpedo, having a projecting ring secured to its upper portion, and a projecting ring secured to its lower portion, the first mentioned ring having interspaced lugs projecting from and around its outer surface, and the other ring having interspaced lugs projecting from and around its inner surface. 75

3. A plurality of explosive cans, or torpedoes, one having a projecting ring secured to its upper portion, said ring having interspaced lugs projecting from and around its outer surface, and an annular groove 85 below said lugs, the other a projecting ring secured to its lower portion, said ring having interspaced lugs projecting from and around its inner surface.

4. An explosive can or torpedo, having a projecting ring secured to its upper portion, said ring having interspaced lugs projecting from and around its outer surface, and an annular groove below said lugs, and a projecting ring secured to its lower portion, 95 said ring having interspaced lugs projecting from and around its inner surface.

5. A plurality of explosive cans or torpedoes, one having a projecting ring secured to its upper portion, the other a projecting ring secured to its lower portion, the first mentioned ring having interspaced lugs projecting from and around its outer surface, and the other ring having interspaced lugs projecting from and around its inner surface, and a plate, adapted to support the first mentioned torpedo on the mouth of the well tube, removably secured to said torpedo. 100

6. An explosive can or torpedo, having a projecting ring secured to its upper portion, and a projecting ring secured to its lower portion, the first mentioned ring having interspaced lugs projecting from and around its outer surface, and the other ring having interspaced lugs projecting from and around its inner surface, and a plate, adapted to support said torpedo on the mouth of the well tube, removably secured to said torpedo. 110

7. A plurality of explosive cans or torpedoes, one having a projecting ring secured to its upper portion, said ring having interspaced lugs projecting from and around its outer surface, and an annular groove below said lugs, the other having a projecting 115 ring secured to its lower portion, said ring having interspaced lugs projecting from and around its inner surface, and a plate, adapted to support said torpedo on the mouth of the well tube, removably secured to said torpedo.

8. A plurality of explosive cans or torpedoes, one having a projecting ring secured to its upper portion, said ring having interspaced lugs projecting from and around its outer surface, and an annular groove below said lugs, the other having a projecting 120 ring secured to its lower portion, said ring having interspaced lugs projecting from and around its inner surface, and a plate, adapted to support said torpedo on the mouth of the well tube, removably secured to said torpedo. 130

in the groove of the first mentioned torpedo ring.

8. An explosive can or torpedo, having a projecting ring secured to its upper portion, said ring having interspaced lugs projecting from and around its outer surface, and an annular groove below said lugs, and a projecting ring secured to its lower portion, said ring having interspaced lugs projecting from and around its inner surface, and a plate, adapted to support said torpedo on the mouth of the well tube, removably secured in the groove of the upper torpedo ring.

15 9. In combination, an explosive can or
torpedo, having a projecting ring secured
to its upper portion, said ring having inter-
spaced lugs projecting from and around its
outer surface, a ring having interspaced
20 lugs projecting from and around its inner
surface, and a bail pivotally connected with
said last mentioned ring.

10. In combination, an explosive can, or torpedo, having a projecting ring secured to its upper portion, and a projecting ring secured to its lower portion, the first mentioned ring having interspaced lugs projecting from and around its outer surface, and the other ring having interspaced lugs projecting from and around its inner surface, and a bail pivotally connected with said ring.

11. An explosive can or torpedo, having
35 a projecting ring secured to its upper por-
tion, said ring having interspaced lugs pro-
jecting from and around its outer surface,
and an annular groove below said lugs, and
40 a ring having interspaced lugs projecting
from and around its inner surface, and a
bail pivotally connected with said last men-
tioned ring.

12. An explosive can or torpedo, having a projecting ring secured to its upper portion, said ring having interspaced lugs projecting from and around its outer surface, and an annular groove below said lugs, and a projecting ring secured to its lower portion, said ring having interspaced lugs projecting from and around its inner surface, and a ring having interspaced lugs projecting from and around its inner surface, and a bail pivotally connected with said ring.

13. An explosive can or torpedo, having
55 a projecting ring secured to its upper por-

tion, said rings having interspaced lugs projecting from and around its outer surface, and a plate adapted to support said torpedo on the mouth of the well tube, removably secured to said torpedo, and a ring having interspaced lugs projecting from and around its inner surface, and a bail pivotally connected with said ring. 60

14. An explosive can or torpedo, having a projecting ring secured to its upper portion, and a projecting ring secured to its lower portion, the first mentioned ring having interspaced lugs projecting from and around its outer surface, and the other ring having interspaced lugs projecting from and around its inner surface, and a plate adapted to support said torpedo on the mouth of the well tube, removably secured to said torpedo, and a ring having interspaced lugs projecting from and around its inner surface, and a bail pivotally connected with said ring. 65
70
75

15. An explosive can or torpedo, having a projecting ring secured to its upper portion, said ring having interspaced lugs projecting from and around its outer surface, and an annular groove below said lugs, and a plate adapted to support said torpedo on the mouth of the well tube, removably secured to the groove of the upper torpedo ring, and a ring having interspaced lugs projecting from and around its inner surface, and a bail pivotally connected with said ring. 80 85

16. An explosive can or torpedo, having a projecting ring secured to its upper portion, said ring having interspaced lugs projecting from and around its outer surface, and an annular groove below said lugs, and a projecting ring secured to its lower portion, said ring having interspaced lugs projecting from and around its inner surface, and a plate adapted to support said torpedo on the mouth of the well tube, removably secured to the groove of the upper torpedo ring, and a ring having interspaced lugs projecting from and around its inner surface, and a bail pivotally connected with said ring. 90 95 100

In testimony of which invention, I have hereunto set my hand, at Bradford, Pa., on this ninth day of March, 1909.

ROBERT S. PRINGLE.
